UNITED STATES PATENT OFFICE.

RALPH S. MEGATHLIN, OF QUINCY, MASSACHUSETTS, ASSIGNOR TO UNITED SHOE MACHINERY CORPORATION, OF PATERSON, NEW JERSEY, A CORPORATION OF NEW JERSEY.

METHOD OF PREPARING HEEL BLANKS.

Application filed May 5, 1922, Serial No. 558,684. Renewed October 18, 1926.

This invention relates to the preparation of heel blanks, and is illustrated as utilized in fitting low blanks for rubber heel bases by gouging out the seat surface of each blank 5 and deepening the gouge at the breast end to form a scallop which is known in the art as a "blended Coburn lip".

Until recently it has been necessary to prepare heel blanks, by assembling and securing together a plurality of lifts, forming a gouge on the seat surface of each blank and deepening it at the heel breast end to form a "Coburn lip", by two separate operations. It has recently been suggested that the two 15 operations could be performed in a single machine, shown as comprising a cutter and a turret carrying a plurality of heel holders, each controlled by a cam to force a heel blank therein toward the cutter near the end 20 of the gouging cut to deepen the gouge to form a scallop fitting over the shank part of the shoe, forming the desired "blended lip" or "blended Coburn lip". This machine is shown in United States Letters Patent 25 No. 1,396,143, granted Nov. 8, 1921, on application of Joseph H. Pope, now Reissue No. 15,448.

The present invention relates to a method of preparing heel blanks which is different 30 from that employed when the patented machine is used and which is especially well adapted for preparing certain kinds of heel blanks such as the low rubber-heel bases now used in most men's and in many women's 35 shoes. According to the present invention, a plurality of lifts are assembled and secured together to form a comparatively thin assembled blank such as a rubber-heel base; and then the blank is distorted and that portion 40 which projects beyond a fixed plane is removed in such manner as to form a gouge throughout the major portion of the blank and a blended scallop at the extreme breast end. In order to facilitate the distorting 45 operation, one of the lifts of the assembled blank preferably has a cut-away middle portion so that the blank is considerably thinner at its middle than at its other localities and is thereby more readily distorted than 50 would otherwise be the case. This method is also of advantage in saving stock, since the lifts having cut-away middle portions may, if desired, be made horse-shoe shaped

and may be cut from a sheet of stock by reversing the die between successive cuts to 55 interlock the lifts in a well-known manner.

Although the invention may be carried out by the use of hand tools, it will preferably be practised commercially with the aid 60 of a machine.

Referring now to the accompanying drawings,

Fig. 1 is a cross-section longitudinally of a machine for distorting and cutting the 65 blank;

Fig. 2 is a side elevation of the work-engaging parts of the co-operating rolls;

Fig. 3 is a section, partly broken away, 70 through the rolls, on an enlarged scale;

Figs. 4, 5 and 6 are views showing the successive steps of preparing a heel blank according to my novel method; and

Fig. 7 is a longitudinal section of a heel blank as so prepared.

As shown in Fig. 1, the general organization of the machine comprises co-operating heel blank feeding and distorting rolls 10 and 12, a stationary knife 14 to skive the waste material from heel blanks distorted thereby, and mechanism automatically to 75 present heel blanks successively thereto. The heel blanks are stacked on a stationary table 16 in a magazine 18, under a presser 20, and are advanced successively to the rolls by a pusher 22 reciprocating over the table. 85 Parts not hereinafter fully described may be, and are shown as being, the same as those described in United States Letters Patent No. 961,736, granted June 14, 1910, on application of J. R. Scott, and No. 90 1,300,627, granted April 15, 1919, on application of E. E. Lane.

As shown in Fig. 2, roll 10 comprises a plurality of sections formed with teeth which sink into the waste portion of the 95 work to a greater or less extent. To distort the blanks against the teeth of roll 10, roll 12 is formed with a cavity 24 deep enough along its front and sides to protect the sides and rear end of a heel blank, as shown at 26. 100 An intermediate portion 28, extending from B to C, in Fig. 3, which grades into the deep portion 26 from A to B, is of an intermediate depth, and is substantially concentric of the roll, to form the flat bottom 56 105 of the gouge in each heel blank H (Fig. 7).

The intermediate portion 28 grades into a shallow portion 32, extending from C to D, which forms the lip 58.

By comparing Figs. 2, 3, 6 and 7, it will be seen that roll 12 is formed with a sharp rise at the beginning of the portion A—B, firmly to grip the blank and carry its forward edge under knife 14, then a portion A—B of gradually increasing radius to form the bevel 54, then a concentric portion 28 extending from B to C to form the bottom 56 of the gouge, and finally a portion 32 extending from C to D to form the lip 58. The portion 26 is made somewhat larger than the usual blanks, to permit use of the roll on larger blanks if desired. Although when so used the size of gouge and lip is the same as on the smaller blanks, it is often desirable thus to vary the size of the blanks without changing the treatment of them.

If this machine were used on hard blanks made in the usual way by assembling whole lifts, it will be apparent from an inspection of Fig. 2 that the operator would have to choose between providing long, slender, easily-broken teeth on roll 10, and allowing the blank to exert a tremendous pressure wedging rolls 10 and 12 apart. To obviate both difficulties I prepare the blanks according to a novel method comprising the steps of assembling one or more whole lifts 50 with a lift 52 having a cut-away middle portion, said lift being herein shown as of horseshoe-shape, and then distorting and skiving the blank so formed, in a machine of the type illustrated, as above described. As shown in Fig. 2, this assembly is sufficiently near the desired final shape that the usual short, strong teeth may be employed on roll 10 without any undue pressure tending to wedge rolls 10 and 12 apart.

In carrying out my invention, a number of heel blanks of the form shown in Fig. 5 are made up, each being formed by assembling one or more lifts 50, with a lift or rand 52, and these blanks are placed in the magazine 18 under the presser 20. Thereafter pusher 22 advances the heel blanks successively to rolls 10 and 12, which cooperate with knife 14 to form on each heel blank a gouge 56 and an adjoining blended lip 58.

The machine which has been described

above is not herein claimed but forms the subject-matter of divisional application Ser. No. 14,294, filed March 9, 1925.

Having described my invention, what I claim as new and desire to secure by Letters Patent of the United States is:

1. That method of preparing heel blanks which comprises the steps of assembling and securing together a whole lift 50 and a lift 52 formed like a rand in a horseshoe shape, then progressively distorting the blank made up of the assembled lifts by forcing the central part of the blank upward against a set of feed teeth, the absence of material from the center of the horseshoe-shaped lift serving to prevent lifting the feed teeth from the sides of the blank and to prevent undue pressure on the teeth at the center of the blank, and finally removing the material which is forced above a fixed plane in such manner as to form a gouge and an adjacent blended scallop. 75

2. That method of preparing heel blanks which comprises the steps of assembling and securing together a lift 50 and a horseshoe-shaped rand 52 to form a blank, and then distorting the assembled blank and removing that part thereof which is brought above a fixed plane in such a manner as to form a gouge and an adjacent blended Coburn lip. 80

3. That method of preparing heel blanks which comprises assembling and securing together a whole lift and a lift having a cut-away middle portion and then distorting the assembled blank and removing that portion thereof which is caused to project beyond a fixed plane in such manner as to form a gouge throughout the major portion of the blank and a blended scallop at the extreme breast end. 90

4. That method of preparing heel blanks which comprises assembling and securing together a plurality of lifts to form a rubber-heel base, and then distorting the assembled blank and removing that portion thereof which is caused to project beyond a fixed plane in such manner as to form a gouge throughout the major portion of the blank and a blended scallop at the extreme end. 100

In testimony whereof I have signed my name to this specification.

RALPH S. MEGATHLIN.
